UNITED STATES PATENT OFFICE.

ROBERT LUKE HOWARD, OF LUTON, COUNTY OF BEDFORD, ENGLAND.

WIRING FOR SECURING STOPPERS TO BOTTLES.

SPECIFICATION forming part of Letters Patent No. 329,169, dated October 27, 1885.

Application filed September 17, 1885. Serial No. 177,318. (No model.) Patented in England March 2, 1880, No. 926.

To all whom it may concern:

Be it known that I, ROBERT LUKE HOWARD, a subject of the Queen of Great Britain, residing at Luton, in the county of Bedford, England, have invented a certain new and useful Wiring for Securing Stoppers in Bottles, of which the following is a specification.

In the specification of patent application filed by me on the 3d of May, 1884, I have described a wiring for securing stoppers in bottles and means for forming the wiring on the stopper and bottle.

Figure 1 of the accompanying drawings is a perspective view, and Fig. 2 a plan, of this wiring as applied to the securing of a stopper in a bottle.

It consists of two pieces of wire, A, passing across the cork or other stopper, and two

pieces, B, passing around the bottle-neck and below the band thereof. All four pieces of wire are twisted together at each side of the bottle, as shown at C and D.

I claim—

The wiring for corks or stoppers of bottles, composed of four pieces of wire twisted together at opposite sides of the bottle-neck, two pieces thereof going across the cork or stopper to hold the same, and the other two around the neck to form the band, substantially as set forth.

ROBERT LUKE HOWARD.
